UNITED STATES PATENT OFFICE

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE

BASE FOR MOTION PICTURE PROJECTION MACHINES

Application filed May 31, 1928. Serial No. 281,870.

This invention relates to motion picture apparatus and more particularly to a new and improved base for supporting the various parts thereof.

5 The invention provides a base for machines of the above type which includes a plurality of widely separated feet having adjustable means for contacting with a floor or other supporting surface. The feet are so arranged and located that a comparatively large area is subtended thereby, whereby the machine is more rigidly supported. A central adjustable supporting member is also included for carrying the weight of the central part of the 10 base and the apparatus associated therewith, whereby the tendency of the base to warp is eliminated. The base is further so designed that it may be readily and cheaply formed from a single casting.

20 The invention also consists in certain new and original features of construction and combinations of parts hereinafter set forth and claimed.

Although the novel features which are believed to be characteristic of this invention 25 will be particularly pointed out in the claims appended hereto, the invention itself, as to its objects and advantages, the mode of its operation and the manner of its organization 30 may be better understood by referring to the following description taken in connection with the accompanying drawings forming a part thereof, in which

Figure 1 is a plan view of a base for a motion picture projecting machine constructed 35 in accordance with the present invention.

Figure 2 is a side elevation thereof, partly in section.

Figure 3 is a rear elevation of the base 40 shown in Figure 1; and

Figure 4 is a detailed sectional view of one of the supporting feet showing the pressure cup in position.

Like reference characters denote like parts 45 in the several figures of the drawings.

In the following description and in the claims parts will be identified by specific names for convenience, but they are intended to be as generic in their application to similar parts as the art will permit.

Referring to the drawings more in detail the invention is shown as comprising a base formed of a body section 10 having an enlarged circular portion 11 at one end thereof for supporting the pedestal of a motion picture machine and provided with a plurality of outwardly extending legs 12 located adjacent said enlarged section 11. The opposite end of said base is formed with a pair of legs 13 extending outwardly and at right angles therefrom and being provided at their outer portions with a pair of raised flat surfaces 15 which are adapted to receive and support the rear braces of the machine. Legs 13 are provided, intermediate surface 15 and body portion 10, with a pair of oval openings 16 through which the telescoping brace members are adapted to pass.

Enlarged section 11 includes a raised flat ring shaped surface 17 suitably drilled as at 18 to provide means for securing the pedestal of the motion picture projection machine thereto. Surface 17 corresponds to a cooperating surface on the bottom of the pedestal member.

In the central portion of body member 10 a raised ring shaped section 19 is provided having a machined surface and suitably drilled as at 20 to receive and support an operating switch. At the rear of said ring 20 the base includes a circular conduit opening 21 through which the electric conduit for supplying power to the machine may be passed. The base is formed with a circular outline adjacent said conduit opening in 85 order to increase the total area thereof and form a more rigid assembly.

The various legs 12 and 13 are provided at their extremities with feet members 22 which are suitably drilled and tapped to receive 90 supporting screws 23. Screws 23 are provided with rounded end sections 24 which are adapted to contact with the spherical surfaces 25 in pressure cups 26, said cups being supported from the floor of the projection room. An additional foot 27 is provided at the rear of base 10 and is adapted to receive a supporting screw 28. The central portion of base 10 is drilled as at 30, intermediate ring 19 and enlarged portion 11, for receiving 95 100

supporting screw 31, which is adapted to carry the weight of the central portion of the base and eliminate any bending moment which might otherwise be present, and to prevent vibrations within the base itself.

The base above described is supported from the floor at six different positions, including four outwardly extending legs, rear supporting screw 28 and central screw 31. An extremely accurate adjustment may consequently be obtained and the various bending moments be eliminated. In addition, various webs 32 are extended across said base in both transverse and longitudinal directions for further strengthening the assembly. Webs 32 are preferably cast with the base and form an integral part thereof. The particular arrangement of supporting feet is such that a maximum amount of floor area is covered by the base, whereby the center of gravity of the associated machine may be varied within wide limits without impairing the stability of the apparatus.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A base for a motion picture projecting apparatus comprising an elongated body portion having an enlarged circular section for receiving the pedestal of the projection apparatus, a pair of supporting legs extending outwardly from said pedestal supporting section, a second pair of supporting legs located at the rear of said base and means located at an intermediate portion of said base for independently supporting the same.

2. A base for a motion picture projecting apparatus comprising an elongated body portion having an enlarged circular section for receiving the pedestal of the projection apparatus, a pair of supporting legs extending outwardly from said pedestal supporting section, a second pair of supporting legs located at the rear of said base and means located at an intermediate portion of said base for independently supporting the same comprising a threaded member carried by said base and adapted to contact with a supporting surface.

3. A base for a motion picture projecting apparatus comprising an elongated body portion, the forward portion of said base being of enlarged dimensions and adapted to receive the pedestal of the projection machine, supporting legs extending outwardly from said enlarged portion, a pair of supporting legs at the rear of said base, each of said last mentioned legs being provided with means

for supporting the rear braces of the projection machine, adjustable supporting members carried in each of said legs, an additional adjustable supporting member at the rear of said body portion, and a sixth supporting means located centrally of said body portion at the rear of said pedestal support.

4. A base for a motion picture projection apparatus comprising an elongated body portion of substantial width having longitudinal and transverse re-enforcing webs formed integrally therewith, a pedestal receiving section, a pair of outwardly and forwardly extending legs adjacent said pedestal receiving section, a pair of legs extending transversely of said base at a substantial distance from said first mentioned legs, supporting feet associated with each of said legs, and a fifth supporting foot located at the rear of said body section.

5. A base for a motion picture projection apparatus comprising an elongated body portion of substantial width having longitudinal and transverse re-enforcing webs formed integrally therewith, a pedestal receiving section, a pair of outwardly and forwardly extending legs adjacent said pedestal receiving section, a pair of legs extending transversely of said base at a substantial distance from said first mentioned legs, supporting feet associated with each of said legs, a fifth supporting foot located at the rear of said body section, and a sixth supporting member located at the center of said body section.
